UNITED STATES PATENT OFFICE

168,022

TIRE

Harold W. Delzell, Akron, Ohio, assignor to The
B. F. Goodrich Company, New York, N. Y., a
corporation of New York

Application June 14, 1952, Serial No. 20,209

Term of patent 14 years

(Cl. D90—20)

To all whom it may concern:

Be it known that I, Harold W. Delzell, a citizen of the United States of America residing at Akron, in the county of Summit and State of Ohio, have invented a new, original, and ornamental Design for a Tire, of which the following is a specification, reference being had to the accompanying drawing, forming a part thereof.

In the drawing:

The figure is a perspective view of a tire, embodying my new design.

I claim:

The ornamental design for a tire, as shown.

HAROLD W. DELZELL.
